UNITED STATES PATENT OFFICE.

OTTO W. MÜLLER, OF MARLBORO, AND WILHELM F. HEIDELMANN, OF NEW YORK, N. Y.

CLOTHES-LINE SUPPORT.

1,200,822.

Specification of Letters Patent.

Patented Oct. 3, 1916.

Application filed March 11, 1916. Serial No. 33,596.

To all whom it may concern:

Be it known that we, (1) OTTO W. MÜLLER and (2) WILHELM F. HEIDELMANN, subjects of the Emperor of Germany, residing at (1) Marlboro and (2) New York, in the counties of (1) Ulster and (2) New York, State of New York, have invented certain new and useful Improvements in Clothes-Line Supports; and we do hereby declare the following to be a full, clear, and exact description of the invention, such as will enable others skilled in the art to which it appertains to make and use the same.

This invention relates to new and useful improvements in clothes line supports and the principal object of the invention is to provide a window support for clothes lines which is adapted for attachment to the ordinary window casing without injuring the same.

Another object of the invention is to provide a device which may be easily and cheaply constructed of any suitable material and which when not in use may be folded downwardly so as to allow the window to be closed.

With these and other objects in view, the invention consists in the novel combination and arrangement of parts which will be fully set forth in the following specification and accompanying drawings, in which:

Figure 1 is a sectional view through a window illustrating this improved device in position for the clothes to be attached thereto, and Fig. 2 is a view of the device in its inoperative position or in folded position when the clothes are on the line, and Fig. 3 is a detail perspective view of the plate on which the line supporting hooks are secured.

Referring to the drawing the numeral 1 designates a window of the ordinary construction provided with the usual upper sash 2 and the lower sash 3. Secured to the window frame near the joint of the upper and lower sashes is the plate 4 which is best illustrated in Fig. 5 consisting of a rectangular sheet of metal provided with suitable hooks 5. These hooks turn upwardly as clearly shown in Fig. 3 and are arranged to support the clothes line as clearly shown in the drawings.

Secured at a point slightly above the plate 4 is a suitable screw eye 6 and at a point somewhat below the plate is a suitable screw eye 7. These screw eyes 6 and 7 are respectively adapted to support the sup-

porting arm and the brace arm which will be more fully hereinafter described.

The supporting arm above referred to consists of a rod 8 having a loop 9 formed at one end which passes through the screw eye 6 and the opposite end of said rod is formed with the downwardly extending angular extension 10 having the loop 11 formed thereon. This angular extension 11 and loop 11 are adapted to support the pulley 12 over which the clothes line 13 passes. A suitable pin 14 extends through the rod 8 intermediate its ends and forms an abutment for the brace rod which will be more fully hereinafter described. The brace rod above referred to consists of a rod 15 having a loop 16 formed at one end which extends through the eye of the screw eye 7 and thus pivotally supports the brace rod in place on the window casing, while the opposite end of said rod is provided with the angular extension 17 having the longitudinal slot 18 formed therein.

The slot 18 above referred to is adapted to receive the rod 8 as clearly illustrated in Fig. 1 and it will thus be seen that when the supporting arm is in use, the outer side of the rod will engage the pin 14 thereby holding the supporting arm in horizontal position.

In order to hold the device against swinging movement when in the position shown in Fig. 1, a suitable hook 19 is secured to the window casing as at 20 and is adapted to have its hooked end pass over the horizontal supporting bar thereby holding the device rigid.

It will be apparent from the foregoing that when in use the device is raised in the position shown in Fig. 1 and the clothes hung on the line 13. After the desired number of clothes has been put on the line it will be apparent that the lower run of the line is hooked over the lower hook 5 and the arm may be lowered as shown in Fig. 2 thereby permitting the window to be closed without loosening the tension on the line. In this way it will be apparent that a particularly simple and efficient clothes line support is provided which will enable the clothes to be hung on the same without necessitating the person using the device leaning out of the window.

While in the foregoing there has been shown and described the preferred embodiment of this invention, it is to be under-

stood that such changes may be made in the combination and arrangement of parts as will fall within the spirit and scope of the appended claims.

5 What is claimed is:

1. A clothes line support comprising a pivoted supporting arm, an angular extension at the free end of said arm, a pulley carried by said angular extension, a pin extending through the supporting arm intermediate its ends thereof, a supporting bracket pivoted at one end to the window casing, an angular extension in the opposite end of the bracket, said angular extension being provided with a longitudinal slot for the reception of the supporting arm, the extension engaging the pin to hold the arm in its raised or horizontal position, and a hook to hold the device rigid when in its horizontal or raised position.
- 10 2. A clothes line support comprising a supporting arm pivotally secured at one end to a window casing, an angular extension at the free end of said arm, a clothes line supporting pulley carried by said angular ex-

30 tension, a stop pin arranged through said supporting arm intermediate its ends thereof, a supporting bracket pivotally secured at one end to the window casing, an angular extension formed on the free end of the bracket, said angular extension being provided with a longitudinal slot slidably receiving the supporting arm, said extension of the bracket engaging the stop pin of the arm to hold the same in a raised or horizontal position, and a hook pivotally secured to the window casing adapted to engage the arm to hold the device rigid when in a raised or horizontal position.

35 In testimony whereof we affix our signatures in presence of two witnesses:

40 OTTO W. MÜLLER.

WILHELM F. HEIDELMANN.
